FREQUENCY MODULATION RECEIVER SQUELCH CIRCUIT

Dudley E. Foster, South Orange, N. J., assignor
to Radio Corporation of America, a corpora-
tion of Delaware

Application June 19, 1941, Serial No. 398,703

10 Claims. (Cl. 250—20)

My present invention relates to receivers of angular velocity-modulated carrier waves, and more especially to frequency modulated carrier wave receivers embodying inter-channel noise squelch circuits.

One of the main objects of my present invention is to provide a receiver of angular velocity-modulated carrier waves (this term being generic for frequency, or phase, modulated carrier waves) which employs an amplitude modulation limiter network for an additional function, to wit: the suppression, or squelching, of inter-channel noises.

Another important object of my invention is to provide an amplitude limiter for a frequency modulated carrier wave (FM) receiver which has the auxiliary function of preventing reproduction of electrical impulses in response to a decrease of received signals below a predetermined intensity value.

Another object of my invention is to apply noise squelching action to a point in the FM receiver system prior to the detector, and the squelching function being performed by a prior signal transmission tube.

Still other objects of my invention are to improve generally the simplicity and efficiency of noise suppression devices for FM receivers, and more especially to provide noise squelch circuits which are reliable in operation, and are economically manufactured and assembled in FM receivers.

The novel features which I believe to be characteristic of my invention are set forth in particularity in the appended claims; the invention itself, however, as to both its organization and method of operation will best be understood by reference to the following description undertaken in connection with the drawing in which I have indicated diagrammatically a circuit organization whereby my invention may be carried into effect.

In the drawing:

Fig. 1 shows the circuit diagram of an embodiment of the invention.

Fig. 2 shows the limiter characteristic.

Referring, now, to the accompanying drawing, the invention is shown applied to the intermediate frequency (I. F.) network of a superheterodyne receiver adapted to be used in the FM band of 42-50 megacycles (mc.). The networks prior to the limiter are not shown, since they are well known to those skilled in the art. The channel width in FM reception is 200 kilocycles (kc.); that is, the maximum permissible deviation of the carrier is 100 kc. to each side of the carrier, or center, frequency of the wave. It is well known, of course, that there is radiated from the FM transmitter a wave whose carrier amplitude is constant, but whose frequency is

deviated in accordance with the amplitude of the modulating signal, the rate of deviation being dependent upon the modulation frequency. The collected FM waves are usually converted to a lower value of frequency; that is, the center frequency is reduced to the I. F. value. The latter may be of the order of 4.3 mc. The frequencies given herein are purely illustrative and are not to be considered as limiting.

10 The FM waves, with the center frequency at I. F., may be amplified by one or more I. F. amplifiers. In the I. F. transmission network is included an amplitude modulation limiter. The limiter acts to prevent amplitude modulation effects on the FM carrier from passing to the detector. Noise impulses, the various tuned circuits and fading cause amplitude variation to appear on the FM carrier waves. The output of the detector must be representative of the 15 modulation signal applied to the carrier at the transmitter. Since the modulation appears on the carrier as a frequency variation of the carrier, any amplitude variation in the latter gives rise to distortion. Hence, there is used a 20 device, which has a flattened output above a predetermined carrier input intensity, for eliminating the amplitude variation of the carrier.

In Fig. 1 the limiter tube 1 is of the pentagrid type. Its cathode 2 is connected through a resistor R₁ to a highly negative point on the direct current voltage supply potentiometer of the receiver. It is to be understood that R₂ represents a resistor connected between the negative terminal of the direct current source and ground.

30 35 The grid 4, located between the positive screen grids 3 and 5, is connected to the high potential side of the resonant input circuit 10. The latter is tuned to the center frequency, the I. F. value, of the FM waves. The cathode 2 is connected to the low potential side of input circuit 10. The resonant input circuit 10, which may be in the plate circuit of the converter or an I. F. amplifier tube, is tuned to the I. F. value. Circuits 11 and 10 are reactively coupled so as 40 45 to pass a band up to substantially 200 kc. thereby permitting the maximum frequency deviations to be transmitted to the detector.

The plate 6 is connected to the high potential side of circuit 12 which is tuned to the I. F. value, and the low potential side of the circuit 12 is connected to the positive terminal of a direct current source. The grid 1' is connected to a voltage point which maintains the grid at a relatively low positive voltage, say about +2 volts. Grids 3 and 5 are maintained at a positive potential of about +15 volts. The leads to each of grids 1', 3 and 5 are by-passed for I. F. currents. The voltage supply lead to the plate may be by-passed to the cathode for I. F. currents. The output circuit 12 is reactively cou-

pled to the tuned circuit 13. The latter is resonated to the I. F. value, and the coupling between circuits 12 and 13 is chosen to permit the network 12-13 to pass the desired frequency deviations up to about 200 kc.

The I. F. amplifier tube 20 has its cathode grounded, while its signal control grid is connected to the high potential side of input circuit 13. A direct current blocking condenser is connected between the grounded cathode and the low potential side of circuit 13. The plate circuit of amplifier 20 may be coupled to the discriminator of any well known form of FM detector circuit. It is not believed necessary to describe the details of such a detector circuit, since those skilled in the art are fully acquainted with the various types of FM detectors that may be utilized. It is sufficient to point out that the FM detector circuit transforms the constant amplitude-variable frequency wave into a modulated carrier wave of constant carrier frequency and variable amplitude. The resulting amplitude modulated carrier wave is rectified to produce the modulation voltage, which may then be amplified and reproduced.

The limiter characteristic is shown in Fig. 2. In that figure "Plate current" is plotted against "Signal grid-volts." The symbol I_p designates the variation of plate current of tube 1 as the signal grid voltage applied to grid 4 is varied in a negative direction and a positive direction relative to zero bias. It will be observed that beyond a predetermined signal grid voltage the plate current flowing in the output circuit of tube 1 substantially flattens out. It is sufficient for the purposes of this application to explain that the limiter circuit shown herein is operated so that the plate current is sharply cut off by negative signal grid voltage, and reaches saturation with a small positive signal grid voltage. Both polarities of the signal voltage are thus clipped in the tube, and the fundamental component of the plate current is selected in the plate circuit. Where the tube 1 is of the 6A8 type, substantially constant output is secured above a predetermined signal grid voltage. The potentials of grids 1' and 3 control the plate current at which saturation occurs, grid 2' having a negligible effect because it consists only of supporting rods.

The potential of grid 3, which is internally connected to grid 5, is preferably between 10 and 15 volts positive. The limiter output may, of course, be adjusted to meet the requirements of the particular receiver designated, it being pointed out that as grid 1' is made increasingly positive the plate current saturates at higher values of grid 4 voltage and higher plate current. For maximum limiter sensitivity and flatness the signal should be clipped symmetrically on both polarities, and in the 6A8 tube the signal is clipped almost symmetrically without any bias on the signal grid. It will, therefore, be seen that the limiter tube is one of the space charge grid type and that plate current flows through the resistor R_1 when the limiter has signal voltage of significant amplitude applied thereto.

To provide noise suppression, when signal amplitude is below a predetermined tolerable level, the low potential side of circuit 13 is connected by direct current voltage lead 30 to the cathode end of resistor R_1 . Therefore, the signal grid of tube 20 is connected to a point of high negative voltage on resistor R_2 through a path which includes the coil of circuit 13, lead 30 and resistor R_1 . Hence, when no FM waves are being

received the current flow through limiter tube 1 is obviously substantially zero. Hence, there is a small voltage drop through resistor R_1 . Accordingly, it will be seen that in the no-signal state the bias applied to the signal grid of tube 20 is the high negative voltage across R_2 minus the small voltage drop across resistor R_1 . The negative voltage across section R_2 is chosen so that it is sufficiently high to bias tube 20 substantially to plate current cut-off. This prevents the transmission of any electric impulses to the following FM detector. Hence, interchannel noises, as well as noises existing during abnormally weak signal reception, are prevented from being reproduced. Further, tube hiss will not be passed on to the detector.

However, when the FM waves applied to the limiter input circuit are of an amplitude above a predetermined level the plate current flowing through R_1 is a maximum, and, therefore, the voltage drop across resistor R_1 is a maximum. The magnitude of resistor R_1 is chosen so that at the amplitude of applied signals sufficient to operate the limiter the drop across R_1 reaches full value. In this state, the difference in voltage drop across R_1 and R_2 is such as to give normal bias to tube 20. That is, with limiting value of the plate current flow the voltage across resistor R_1 will be sufficiently high in magnitude, and opposite in polarity, relative to the negative voltage across R_2 so that the bias on the signal grid of amplifier 20 will be reduced to the normal operating value for the amplifier.

In other words, when FM waves of proper strength are applied to the limiter the amplifier tube 20 is normally rendered effective or operative, and reproduction is had. It will, therefore, be seen that if at the limiting value of the plate current of tube 1 the effective bias on the signal grid of tube 20 is normal, then with no signal applied to the receiver the effective bias on tube 20 will be cut-off bias with consequent low gain thereby decreasing the reproduction of noise and spurious responses. The present arrangement has the advantage over the application of other known forms of noise suppression circuits in that it is free from distortion; a better time constant can be designed in this circuit; and it will be quieter in operation.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In a receiver of angular velocity-modulated carrier waves of the type provided with at least two cascaded modulated carrier wave transmission networks prior to the detection network, the method which includes normally rendering the second of said transmission networks ineffective for modulated carrier waves of less than a predetermined amplitude, limiting the current output of the first of the transmission networks, deriving a control voltage from the limited current output of said first network, and rendering said second network effective in response to said control voltage.

2. In a frequency modulated carrier wave receiver of the type including an amplitude limiter stage followed by a modulated carrier wave transmission stage, the method which includes

normally preventing transmission through said transmission stage in the absence of frequency modulated carrier waves at the input of said limiter stage above a predetermined intensity level, deriving a control voltage from the limited current output of said limiter stage, and rendering transmission through said transmission stage effective in response to said control voltage.

3. In a receiver of frequency modulated carrier waves, a limiter network including an electron discharge tube provided with input and output circuits, a resistive impedance in the space current path of said limiter tube, a transmission tube having an input circuit coupled to said limiter output circuit, means normally biasing said transmission tube to space current cut-off in the absence of frequency modulated carrier waves at said limiter tube input circuit above a predetermined intensity level, and means responsive to voltage of a predetermined magnitude developed across said resistive impedance for removing said cut-off bias on said transmission tube.

4. In a receiver of frequency modulated carrier waves, a limiter network including an electron discharge tube provided with input and output circuits, a resistive impedance in the space current path of said limiter tube, a transmission tube having an input circuit coupled to said limiter output circuit, means normally biasing said transmission tube to space current cut-off in the absence of frequency modulated carrier waves at said limiter tube input circuit above a predetermined intensity level, and means responsive to voltage of a predetermined magnitude developed across said resistive impedance for removing said cut-off bias on said transmission tube, said limiter tube being of the type including a space charge grid at a small positive voltage, and having a small plate current flow in the absence of input signal voltage.

5. In a receiver of frequency modulated carrier waves, a limiter network including an electron discharge tube provided with input and output circuits, a resistive impedance in the space current path of said limiter tube, a transmission tube provided with input and output electrodes and having an input circuit coupled to said limiter output circuit, means normally biasing said transmission tube to space current cut-off in the absence of frequency modulated carrier waves at said limiter tube input circuit above a predetermined intensity level, and means responsive to voltage of a predetermined magnitude developed across said resistive impedance for removing said cut-off bias on said transmission tube, and said resistive impedance being included in a common direct current voltage path between the input electrodes of said transmission tube and said cut-off bias means.

6. In a receiver of angular velocity-modulated carrier waves of the type provided with at least two cascaded modulated carrier wave transmission tubes prior to the detection network, the method which includes normally biasing the second of said transmission tubes to space current cut-off for modulated carrier waves of less than a predetermined amplitude, limiting the current output of the first of the transmission tubes to remove amplitude modulation effects, deriving a control voltage from the limited current output of said first tube, and reducing said second tube bias in response to said control voltage.

7. In a receiver of frequency modulated carrier waves, a limiter network including an electron discharge tube provided with input and output circuits, a resistive impedance in the space current

5 path of said limiter tube, a carrier frequency transmission tube provided with input and output electrodes and having an input circuit coupled to said limiter output circuit, means normally biasing said transmission tube to space current cut-off in the absence of frequency modulated carrier waves at said limiter tube input circuit above a predetermined intensity level, means responsive to voltage of a predetermined magnitude developed across said resistive impedance

10 for removing said cut-off bias on said transmission tube, said limiter tube being of a type including a space charge grid at a small positive voltage and having a small space current flow in the absence of input signal voltage, and said resistive impedance being included in a common direct current voltage path between the input electrodes of said transmission tube and said cut-off bias means.

15 8. In a receiver of frequency modulated carrier waves, a limiter network including an electron discharge tube provided with input and output circuits, a resistive impedance in the space current path of said limiter tube, a transmission tube having an input circuit coupled to said limiter output circuit, means normally biasing said transmission tube to space current cut-off in the absence of frequency modulated carrier waves at said limiter tube input circuit above a predetermined intensity level, means responsive to voltage of a predetermined magnitude developed across said resistive impedance for removing said cut-off bias on said transmission tube, said biasing means and resistive impedance being arranged in polarity opposition.

20 9. In a receiver of frequency modulated carrier waves, a limiter network including an electron discharge tube provided with input and output circuits, a resistive impedance in the space current path of said limiter tube, a transmission tube provided with input and output electrodes and having an input circuit coupled to said limiter output circuit, means normally biasing said transmission tube to space current cut-off in the absence of frequency modulated carrier waves at

25 said limiter tube input circuit above a predetermined intensity level, means responsive to voltage of a predetermined magnitude developed across said resistive impedance for removing said cut-off bias on said transmission tube, said biasing means and resistive impedance being arranged in polarity opposition, said limiter tube being of the type including a space charge grid at a small positive voltage and having a small plate current flow in the absence of input signal voltage, and said resistive impedance being included in a common direct current voltage path between the input electrodes of said transmission tube and said cut-off bias means.

30 10. In a receiver of angular velocity-modulated carrier waves of the type provided with at least two cascaded modulated carrier wave transmission networks, the method which includes limiting the current output of the first of the transmission networks, deriving a control voltage from the limited current output of said first network, and maintaining said second network effective in response to said control voltage.
